Primary Examiner — Cynthia Underwood

CLAIM

The ornamental design for a cable wrap, as shown and described.

DESCRIPTION

FIG. 1 is a perspective view of a cable wrap;
FIG. 2 is a front elevational view thereof;
FIG. 3 is a right-side elevational view thereof;
FIG. 4 is a left-side elevational view thereof;
FIG. 5 is a rear elevational view thereof;
FIG. 6 is a top plan view thereof; and,
FIG. 7 is a bottom plan view thereof.

FIG. 8 is a perspective view of the present invention with a cable wrapped around it; and,
FIG. 9 is a front view thereof.

The broken lines represent an environment of use and form no part of the claim.
